US0D1083640S

(12) **United States Design Patent** (10) Patent No.: **US D1,083,640 S**
(45) Date of Patent: ** Jul. 15, 2025

(54) **WEARABLE SENSOR**(71) Applicant: **Biolinq Incorporated**, San Diego, CA (US)(72) Inventor: **David Michael Morelock**, Escondido, CA (US)(73) Assignee: **Biolinq Incorporated**, San Diego, CA (US)(***) Term: **15 Years**(21) Appl. No.: **29/876,134**(22) Filed: **May 16, 2023**(51) LOC (15) Cl. **10-04**

(52) U.S. Cl.

USPC ..... **D10/81**; D24/186; D24/216(58) **Field of Classification Search**

(57) **CLAIM**

The ornamental design for a wearable sensor, as shown and described.

DESCRIPTION

FIG. 1 is a front perspective view of a wearable sensor showing the new design;

FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom plan view thereof;
FIG. 8 is a front perspective view of a wearable sensor showing the new design;
FIG. 9 is a front view thereof;
FIG. 10 is a rear view thereof;
FIG. 11 is a left side view thereof;
FIG. 12 is a right side view thereof;
FIG. 13 is a top plan view thereof;
FIG. 14 is a bottom plan view thereof;
FIG. 15 is a front perspective view of a wearable sensor showing the new design;
FIG. 16 is a front view thereof;
FIG. 17 is a rear view thereof;
FIG. 18 is a left side view thereof;
FIG. 19 is a right side view thereof;
FIG. 20 is a top plan view thereof;
FIG. 21 is a bottom plan view thereof;
FIG. 22 is a front perspective view of a wearable sensor showing the new design;
FIG. 23 is a front view thereof;

FIG. 24 is a rear view thereof;
FIG. 25 is a left side view thereof;
FIG. 26 is a right side view thereof;
FIG. 27 is a top plan view thereof;
FIG. 28 is a bottom plan view thereof;
FIG. 29 is a front perspective view of a wearable sensor showing the new design;
FIG. 30 is a front view thereof;
FIG. 31 is a rear view thereof;
FIG. 32 is a left side view thereof;
FIG. 33 is a right side view thereof;
FIG. 34 is a top plan view thereof;
FIG. 35 is a bottom plan view thereof;
FIG. 36 is a front perspective view of a wearable sensor showing the new design;
FIG. 37 is a front view thereof;
FIG. 38 is a rear view thereof;
FIG. 39 is a left side view thereof;
FIG. 40 is a right side view thereof;
FIG. 41 is a top plan view thereof; and,
FIG. 42 is a bottom plan view thereof.
The broken lines are for the purpose of illustrating portions of the article and form no part of the claimed design.
